METHOD OF MAKING INSOLES AND SHEETS THEREFOR

Fred L. Ayers, Watertown, Mass., assignor to
 Brown Company, Berlin, N. H., a corporation
 of Maine

Application December 11, 1937, Serial No. 179,276

3 Claims. (Cl. 12—146)

This invention relates to a method of making insoles and to sheets therefor. It deals more especially with a method and with sheets designed to yield insoles of relatively flexible material throughout excepting at their toe portions, which are of relatively stiff material.

Insoles of relatively high flexibility at the ball zone and of relatively low flexibility at the toe portions and at the shank and heel portions have been introduced into the shoemaking art on the basis that flexibility is desired at the ball zone of the shoe, whereat flexing takes place during wear of the shoe, and that stiffness is desired at the toe portions and at the shank and heel portions during the lasting and other shoemaking operations as well as during wear of the shoe. In order to realize economically stiffness at the insole zones other than the ball zone, it has been the practice to use stiff fiberboard as the material of construction of the insole zones other than the ball zone. Because the shank and heel portions of an insole are so positioned in a shoe as to be exposed to view, the fiberboard material of which such portions are made is, when exposed, apt to be repulsive to the shoe wearer as bespeaking cheapness.

In making shoes, it is usual before lasting to secure to the under or outer face of the insole, as by staples, a stiffener piece or fiberboard blank extending from substantially the front shank line to the heel edge. There is thus no real need for the provision of a stiff heel portion or stiff heel and shank portions in the insole proper. Indeed, it may be desirable to avoid the use of fiberboard in the heel portion or in the heel and shank portions of the insole and its cheap appearance, since the stiffness quality desired at these portions is realized from the stiffener piece or blank usually secured to the under face of the insole and hidden from view. On the other hand, the feature of providing a stiff toe portion, for instance, a stiff fiberboard toe portion, in the insole proper is of primary significance or importance, since the insole toe portion is not exposed to view and it is inexpedient and generally undesirable to secure thereat an extraneous stiffener piece as is usually done under the shank and heel portions.

The insoles produced by the present invention are, therefore, made from relatively flexible material excepting at their toe portions, which may advantageously consist of fiberboard or similar stiff material. The relatively flexible material may advantageously be leather substitute materials, for instance, rubber-impregnated felts, papers, or other fibrous bases. The insole stock

of the present invention takes the form of a sheet comprising at least three zones or strips of material, namely, relatively stiff side zones of a width corresponding substantially to the toe portion of an insole and a relatively flexible intermediate zone sufficiently wide to accommodate all but the toe portions of a two-row cutting pattern wherein in the insole-shank and heel portions of an insole in one row occupies and substantially fits the space between the shank and heel portions of the other row. Such a multi-zone or multi-strip sheet may consist of side strips of stiff fiberboard spliced or joined to an intermediate strip of relatively flexible rubber-impregnated felt. The multi-zone or multi-strip sheet may be made up of five, seven, or other odd number of strips, the odd-numbered strips being the narrow relatively stiff ones and the even-numbered strips being the wide relatively flexible ones; and the narrow strips, other than the marginal ones, may serve to furnish the relatively stiff toe portions of two adjacent rows of insoles. Such a sheet not only lends itself to ready fabrication in long lengths for storage and shipment but may be cut or die cut into the desired insoles with minimum wastage of stock.

With the foregoing and other features and objects in view, the present invention will now be described in further detail with reference to the accompanying drawing, wherein,

Figure 1 shows in perspective a spliced or composite five-strip sheet embodying the present invention and the pattern for cutting such sheet into insoles accordant with the method hereof.

Figure 2 represents a transverse section through the sheet on the line 2—2 of Figure 1.

As appears in Figure 1, the spliced or composite five-strip sheet may be of indefinite length and comprise narrow relatively stiff strips 1, 3, and 5, of substantially equal width spliced to 40 intervening wider relatively stiff strips 2 and 4 at adjoining longitudinal edges e, which may be suitably scarfed and cemented together in lapping relationship to provide substantially smooth or continuous sheet surfaces. It is thus seen 45 that the invention hereof is intended to be applied more especially in instances when the various strips can be cut from material suitable for use in insoles in lieu of leather and available as sheets of indefinite length and of substantially 50 uniform thickness and other qualities throughout. Thus, the strips 2 and 4 may be cut from relatively flexible artificial leather sheet material comprising a base of interfelted fibers formed on a papermaking machine and impregnated 55

- with rubber; and the strips 1, 3, and 5 may be cut from comparatively stiff fiberboard, leatherboard, or the like, all of which are to be regarded as being comprehended by the expression 5 "fiberboard" as used in the appended claims. It might be noted that a soft, absorptive fibrous web or paper of the kind produced from cellulose fiber, such as refined wood pulp or pulp of high alpha cellulose content, on a papermaking 10 machine may be impregnated with rubber latex compositions and then dried to produce artificial leather admirably adapted, because of its more or less stretchable and compressible qualities and its good skivability and other characteristics, for 15 use as the relatively flexible strips 2 and 4 herein; and such artificial leather strips may be spliced with the strips 1, 3, and 5 consisting of comparatively stiff fiberboard, which is inexpensive and can also be skived nicely or without fraying, 20 to produce at low expense the illustrated five-strip sheet from which the desired insoles may be cut by the method hereof. Materials of various other origins or compositions may serve for the odd-numbered and even-numbered strips 25 of the composite sheet hereof, so long as such materials have the degree of flexibility or stiffness required in the odd-numbered and even-numbered strips. The composite or spliced five-strip sheet is preferably of substantial uniform 30 thickness throughout, for instance, of a thickness of about 3 to 4 irons, such as ordinarily desired for insoles; and the adjoining scarfed or beveled edges *e* may be bonded or cemented together by any suitable adhesive, such as rubber 35 latex, rubber cement, glue, etc.

The odd-numbered strips 1, 3, and 5, are of a width approximating or slightly greater than that of the toe portion of the desired insole and the even-numbered strips 2 and 4 are of a width 40 approximating or substantially equal to twice the length of the desired insole minus twice the length *x* of the insole toe portion minus the length *y* of the insole shank and heel portions beginning with substantially its front shank line 45 rearwardly. As depicted, the pattern used for cutting or dieing out insoles from the composite sheet can be made to yield four longitudinal rows of insoles extending transversely of the sheet, since each relatively flexible strip 2 is able to 50 take in or accommodate all but the toe portions *t* of a two-row insole-cutting pattern wherein the shank and heel portions of an insole *m* pointed transversely in one direction in one row occupies and substantially fits the space between the 55 shank and heel portions of two insoles *n* pointed transversely in the opposite directions in the adjacent row. The narrow stiff strip 3 between the wider flexible strips 2 and 4 may be overrun by the oppositely pointed toe portions of the 60 second and third rows of insoles, there being sufficient area in the strip 3 between a pair of insoles in one row to receive the oppositely pointing toe portion of an insole in the adjacent row. It is thus possible to cut the desired insoles from 65 the composite or multi-strip sheet hereof with low stock wastage.

It will be appreciated that while only a five-strip sheet has been illustrated, it is possible to embody the invention hereof in a three-strip 70 sheet, a seven-strip sheet, or other odd-numbered-strip sheet for cutting into the desired insoles, provided that the narrow and relatively stiff odd-numbered strips are spliced or united to the intervening wider and relatively flexible 75 even-numbered strips in such manner that an

intervening strip is capable of yielding all but the toe portions of two rows of oppositely pointed insoles and the bordering narrow strips are capable of yielding the toe portions of such two rows of insoles. In cutting or dieing out insoles, it is, of course, possible to superpose a number of the composite or multi-strip sheets hereof so that a number of insoles will be formed at each insole-cutting or dieing-out operation. The method hereof may be practiced at the shoemaking factory as well as at the plant where the composite or multi-ply sheet material hereof is being fabricated, for such sheet material lends itself to economical shipment either as lengthy sheets or in roll form.

In some instances, the composite sheet hereof may be of unitary or integral structure and consist of an originally relatively flexible sheet throughout, such as a rubber-impregnated, interfelted fiber or paper sheet, whose zones or areas corresponding to the narrow odd-numbered strips 1, 3, and 5 of the composite sheet shown in the drawing have been impregnated additionally with such stiffening media as resin compositions, Celluloid solution, shellac, casein or 20 starch paste, etc., but whose zones or areas corresponding to the even-numbered wider strips 2 and 4 of the composite sheet shown in the drawing are not so impregnated but are left relatively 25 flexible. In other words, the odd-numbered narrow zones or areas may be composed of material originally as flexible as the even-numbered zones or areas but additionally impregnated with suitable stiffening media to a degree such that they 30 can yield insole toe portions of a stiffness quality 35 desired for resisting buckling or distortion of such portions during lasting and wear of the shoes.

The insoles produced accordant with the present invention are appropriately resilient next 40 to the foot all the way from their toe portions to their heel edges. Such stiffness as is desired at the shank and heel portions may be realized by securing to the under or outer face of the insole, as heretofore, a stiffener piece or fiberboard blank extending from substantially the front shank line to the heel edge. The insole hereof thus affords the appropriate resiliency or cushioning effect where the foot bears thereon with maximum pressure, i. e., at the shank and 50 heel zones; it is desirably resilient and flexible at its ball zone; and it is desirably stiff or hard at its toe portion, whereat the foot exerts minimum pressure and whereat it is hence unnecessary to provide resiliency or cushioning effect 55 next to the foot.

I claim:

1. A composite sheet of insole stock adapted to yield upon cutting at least four rows of insoles transversely thereof, said sheet comprising stiff longitudinal areas each of a width to accommodate the toe portion of an insole and alternating with relatively flexible longitudinal areas each of a width to accommodate all but the toe portions of adjacent insoles pointed in opposite directions with the shank and heel portions of one insole fitting the space between the shank and heel portions of adjacent insoles, said relatively stiff areas constituting the margins of said sheet and said sheet comprising at least two of said relatively flexible areas and an intervening relatively stiff area for accommodating the toe portions of adjacent rows of insoles.

2. A composite sheet of insole stock adapted to yield upon cutting at least four rows of insoles 75

transversely thereof, said sheet comprising stiff longitudinal fiberboard strips each of a width to accommodate the toe portion of an insole and spliced to alternating relatively flexible rubber-impregnated fibrous strips each of a width to accommodate all but the toe portions of adjacent insoles pointed in opposite directions with the shank and heel portions of one insole fitting the space between the shank and heel portions of adjacent insoles, said relatively stiff fiberboard strips constituting the margins of said sheet and said sheet comprising at least two of said relatively flexible rubber-impregnated fibrous strips and an intervening relatively stiff fiberboard strip for accommodating the toe portions of adjacent rows of insoles.

3. A method of making insoles that are flexible throughout excepting at their toe portions, which comprises providing a composite longitudinal sheet inclusive of at least three relatively stiff fiberboard strips and at least two alternating relatively flexible rubber-impregnated fibrous strips of a width to accommodate all but the toe portions of adjacent insoles pointed in oppo-

site transverse directions with the shank and heel portions of one insole fitting the space between the shank and heel portions of adjacent insoles, one of said relatively stiff strips being between the two relatively flexible strips and two of said relatively stiff strips constituting the margins of the resulting composite sheet; and cutting from the resulting composite sheet at least four longitudinal rows of insoles extending transversely of said sheet, the cutting pattern for said rows being such that the toe portion in each row of insoles occurs in each said relatively stiff strip and the rest of the insole structure in two adjacent rows of insoles occurs in each said relatively flexible strip with the shank and heel portions of an insole in one row occupying and substantially fitting the space between the shank and heel portions of adjacent insoles in an adjacent row and with the relatively stiff strip between the two relatively flexible strips accommodating the toe portions in two adjacent rows of insoles.
